HAIR CURLER

Frank Pisciotta, St. Albans, N. Y., assignor of fifty
per cent to Louis H. Roth, St. Albans, N. Y.

Application July 5, 1952, Serial No. 297,213

5 Claims. (Cl. 132—40)

1

This invention relates to hair wave devices and more particularly to a hair wave device adapted to be used with home permanent kits which are very popular at the present time.

It is accordingly an object of the present invention to provide devices for hair waving which may be readily and easily applied to the hair for example after application of the home permanent wave solution and which will maintain the hair in a curled condition while applying the neutralizer solution and while setting.

It is a further object of the present invention to provide an improved hair wave device which includes novel means for curling the hair about a spool-like member which tapers inwardly to provide greater curling surface and which is more effective in producing beautiful, natural curls than devices now in use.

It is a still further object of the present invention to provide a novel and highly efficient hair wave device which includes novel means for maintaining a spool-like member in operative position upon the user's hair and which permits ready and easy removal of the same for unwinding and removal of the hair therefrom.

It is a still further object of the present invention to provide an improved hair wave device which includes novel means for aerating and drying the hair while curled upon the spool-like member.

Other objects of the present invention are to provide an improved hair wave device which is of simple construction, is inexpensive to manufacture, has a minimum number of parts, is compact, of pleasing appearance, durable, will have long life and is highly efficient in operation.

For other objects and for a better understanding of the invention, reference may be had to the following detailed description taken in connection with the accompanying drawing, in which

Fig. 1 is a perspective view of a hair wave device embodying the features of the present invention;

Fig. 2 is a cross sectional view taken along line 2—2 of Fig. 1;

Fig. 3 is a cross sectional view taken along line 3—3 of Fig. 2;

Fig. 4 is a perspective view of a modified form of the present invention;

Fig. 5 is a fragmentary exploded view of a portion of the device shown in Fig. 4;

Fig. 6 is a cross sectional view taken along line 6—6 of Fig. 4 and

Fig. 7 is a fragmentary perspective view of a modified form of the present invention.

2

Referring now in detail to the figures, there is shown a spool-like member, referred to collectively as 7, consisting of a central portion 8 and flat circular end portions 9 and 10 integrally connected thereto. The spool-like member 7 is provided with a main hole 11 and auxiliary holes 12 located around the periphery of the end portions 9 and 10 and along the central portion 8, the holes along the central portion communicating with the main hole 11 as clearly shown in Fig. 2. The outer sides of the central portion 8 taper inwardly from the end portions 9 and 10 to the central portion thereof as clearly shown in Fig. 2.

15 Referring now particularly to Figs. 1 and 2, there is shown a clamping member, referred to collectively as 13, and consisting of a flat double pronged part 14, an S-shaped single-pronged part 15 and an elastic band 16 which maintains the parts 14 and 15 in operative engagement.

20 The flat part 14 has an enlarged head portion 17 provided at the center thereof with a hole 18, a neck portion 19 adapted to be engaged by the elastic band 16 and two elongated prongs 20 adapted to receive the spool-like member 7 as shown in Fig. 1.

25 The S-shaped part 15 has a similarly enlarged head portion 21 provided at the center thereof with a hole 22, a neck portion 23 adapted to be engaged by the elastic band 16 and two elongated prongs 24 integrally joined at their ends to form a single prong 25 adapted to engage the hole 11 as shown in Figs. 1 and 2.

30 In operation, the head portions 17 and 21 are compressed as shown in Fig. 2 by the fingers, thus raising the prong 25 from the hole 11 and permitting the ready removal of the spool-like member 7. The strands of hair are then wound around the spool-like member 7 at the central portion 8 thereof by rotating the flat end portions 40 between the fingers as shown in Fig. 3, after applying the permanent waving solution to the hair strands. The hole 11 is then placed once more in engagement with the prong 25, which upon release of the head portions 17 and 21 assumes the position shown in Fig. 1 with the spool-like member 7 firmly engaged between the prong 25 and the lower prongs 20 and having the hair strands firmly curled around the tapered central portion 8. The neutralizing solution may then be applied in a well known manner to the curl, with the main hole 11 and the auxiliary holes 12 providing sufficient aeration to quickly dry and set the hair. After a sufficient 45 interval of time has elapsed, the spool-like mem-

ber 7 may be easily and readily removed in the above described manner to reveal beautiful, natural curls.

Referring now to Figs. 4, 5 and 6, there is shown a modified form of the present invention wherein the prong 25 is modified to an integral plug 26 of polygonal cross section adapted to lockingly engage a modified main hole 26'; also of polygonal cross section, and to prevent angular displacement of the spool-like member 7. The integral plug 26 is provided with an air vent 27 communicating with the main hole 26' whereby excess neutralizing solution may be carried into the main hole 26' and evaporated and which permits increased aeration along with the auxiliary holes 12.

The operation of this modification is the same as that of the device shown in Fig. 1 with the exception that the spool-like member 7 is maintained against angular displacement and increased aeration is provided by the air vent 27.

The integral prong 25 and the plug 26 may be modified or even eliminated without departing from the scope of the present invention, inasmuch as it is apparent that any extension of the prongs 24 which will engage the main hole 11 or 26' will perform the function desired.

Referring now to Fig. 7, there is shown a still further modified form of the present invention wherein the prongs 24 do not come together into an integral large prong 25 but remain separate and extend horizontally across the circular end portion 9 in frictional engagement therewith.

It should now be apparent that there has been provided an improved hair wave device which may be readily and easily applied to the hair and which includes novel means for maintaining the hair in a curled position and for aerating the same, and which may be easily and readily removed at the conclusion of the waving. It should also be apparent that there has been provided an improved hair wave device which includes a spool-like member of novel design which may be manufactured of plastic or other suitable material at a low cost to the consumer and which will maintain the hair in a curled condition until setting.

While various changes may be made in the detailed construction, it shall be understood that these shall be within the spirit and scope of the invention as defined by the appended claims.

Having thus set forth and described the nature of my invention, what is claimed is:

1. A hair wave device comprising in combination a resilient clamping member and a spool-like member adapted to be releasably engaged by said clamping member, said spool-like member consisting of central core and flat discs integrally connected to the ends of said core, the outer sides of said central core tapering inwardly from said discs toward the mid-portion thereof, said clamping member consisting of a flat elongated part and an S-shaped part, said spool-like member resting on said flat elongated part and being provided along the longitudinal axis thereof with a cylindrical hole receiving said S-shaped part, means being provided resiliently securing said S-shaped part along one side thereof to said flat elongated part.

2. A hair wave device comprising in combination a resilient clamping member and a spool-like member, said spool-like member consisting of a central core and flat, substantially circular enlarged end portions integrally connected to the ends of said core, the outer sides of said core

tapering inwardly from said end portions toward the mid-point thereof, said spool-like member being provided with a cylindrical hole along the longitudinal axis thereof extending substantially from end to end, said circular end portions being provided with holes around the peripheries thereof and substantially parallel to said cylindrical hole, said central core being provided with holes communicating with said cylindrical hole, said clamping member consisting of a flat, elongated part and an S-shaped part, said S-shaped part along one side thereof resting on said flat elongated part, means resiliently securing said side of said S-shaped part to said flat elongated part, one end of said S-shaped part extending upwardly at an angle to said flat part, the other end of said S-shaped part extending upwardly from said flat part and extending further substantially parallel to said flat part and terminating in a downwardly bent portion at substantially right angles to said flat part, said spool-like member resting along said flat part on one circular end portion thereof with said downwardly bent portion engaging said cylindrical hole located along the longitudinal axis of said spool-like member.

3. A hair wave device comprising in combination a resilient clamping member and a spool-like member, said spool-like member consisting of a central portion substantially circular in cross section and flat, substantially circular enlarged end portions integrally connected to the ends of said central portion, the outer surface of said central portion tapering inwardly from said end portions toward the mid-point thereof, said spool-like member being provided with a hole extending along the longitudinal axis thereof, said hole being substantially polygonal in cross section, said circular end portions being pierced by a plurality of holes located along the peripheries thereof substantially parallel to said polygonal hole, said central portion being provided with holes communicating with said polygonal hole, said clamping member consisting of a flat, elongated part and an S-shaped part, said S-shaped part along one side thereof resting on said flat part, means resiliently securing said side to said flat part, one end of said S-shaped part extending upwardly from said flat part at an angle thereto, the other end of said S-shaped part being bent upwardly from said flat part, said end being further bent at a substantially parallel direction to said flat part and finally terminating in a downwardly bent portion at substantially right angles to said flat part, said downwardly bent portion being substantially polygonal in cross section and adapted to engage said polygonal hole of said spool-like member, said downwardly bent portion being provided at the top thereof with an air vent communicating with said polygonal hole.

4. A hair wave device comprising in combination a clamping member and a spool-like member, said clamping member consisting of a flat elongated part having an enlarged head, a neck portion and two elongated prongs integrally connected to and extending from said neck portion, an S-shaped part having a corresponding enlarged head portion, a corresponding neck portion adapted to coincide with said first mentioned neck portion and two elongated prongs integrally joined at their ends to form a large prong, elastic means for maintaining the neck of said flat portion in operative engagement with the neck portion of said S-shaped part, said spool-

like member having a cylindrical hole extending along the longitudinal axis thereof and consisting of a central portion substantially circular in cross section and flat circular end portions integrally connected thereto, said circular end portions being pierced by ventilating holes located around the peripheries thereof, said central portion being provided with ventilating holes communicating with said cylindrical hole, the outer surface of said central portion tapering inwardly from said circular end portions, the lower circular end portion of said spool-like member resting on the two elongated prongs of said flat part with the upper end of said cylindrical hole being engaged by said large prong of said S-shaped part.

5. A hair wave device comprising in combination a resilient clamping member and a spool-like member consisting of a central core and flat, substantially circular enlarged end portions integrally connected to the ends of said core, the outer sides of said core tapering inwardly from said end portions toward the mid-point thereof, said spool-like member being provided with a cylindrical hole along the longitudinal axis thereof extending substantially from end to end, said circular end portions being provided with holes

around the peripheries thereof and substantially parallel to said cylindrical hole, said central core being provided with holes communicating with said central cylindrical hole, said clamping member consisting of a flat, elongated part, and an S-shaped part, said S-shaped part along one side thereof resting on said flat, elongated part, means resiliently securing said side of said S-shaped part to said flat, elongated part, one end of said S-shaped part extending upwardly from said flat part at an angle thereto, the other end of said S-shaped part extending upwardly from said flat part and extending further substantially parallel to said flat part, said upwardly extending and horizontally extending portions of said S-shaped part consisting of two elongated prongs, said spool-like member resting along said flat part on one circular end portion thereof with said horizontally extending prongs frictionally engaging the other circular end portion.
